UNITED STATES PATENT OFFICE.

DAVIS A. PICKENS, OF JACKSON, MISSISSIPPI.

SWITCH LUG.

Application filed December 13, 1921. Serial No. 522,032.

To all whom it may concern:

Be it known that I, DAVIS A. PICKENS, a citizen of the United States, residing at Jackson, in the county of Hinds and State 5 of Mississippi, have invented new and useful Improvements in Switch Lugs, of which the following is a specification.

This invention relates to improvements in switch lugs, the principal object of the invention being to provide means for preventing derailment from split switches by the use of spring means for holding the switch point against the rail.

Another object of the invention is to provide means for reinforcing the point so as to make the point as strong as any other part of the track, with means for locking the reinforcement to the point.

This invention also consists in certain other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the several views, and in which:

Figure 1 is a plan view showing a portion of a switch provided with my invention.

Figure 2 is a section on line 2—2 of Figure 1.

Figure 3 is a section on line 3—3 of Figure 1.

Figure 4 is a sectional view taken approximately on line 4—4 of Figure 1.

Figure 5 is a section on line 5—5 of Figure 4.

Figure 6 is an end elevation of the spring carrying member.

Figure 7 is a view showing a modified form of the key used in my invention.

Figure 8 is a section on line 8—8 of Figure 4.

In these views A indicates the main line and B the branch line, C indicating the switch. The switch points 1 of this switch are provided with the reinforcing strips 2 which are connected with the webs of the points and rest upon the base flanges. Each reinforcement is provided with an opening 3 which

has its lower part of less dimensions than its upper part, the upper part being designed 55 to receive the head of a key 4, the shank of which passes through the lower part of the opening and through the bridle rod 5 which is provided with a longitudinally extending slot to receive the lower head of the key. 60 The parts are so formed that the reinforcing strips must be placed in a position parallel with the bridle rods in order to permit the keys to be placed in engagement with the bridle rod. Then by turning the reinforcements at right angles to the bridle rod 65 the head at the lower end of the key will be placed in such a position as to lock the parts together. Locking strips 6 are bolted to the upper and lower faces of the rod 5 and about 70 the keys to prevent turning movement thereof. The upper strips are provided with notches at the outer ends for engaging the shanks of the keys and the flanges of the points are also notched, as at 7, to receive the 75 ends of these strips.

A block 8 is secured to a part of the track, between the switch points, and a spring plunger 9 is located in a guideway 10 in said block. A cross piece 11 is connected 80 with this plunger and rods 12 connect the cross piece with the reinforcement of the point, which acting under the tension of the spring tend to hold the point against the rail of the main track.

Instead of making the keys 4 with a head at both ends I may omit the head at the lower end and screw thread this end, as shown at 4', so that a nut 4'' can be placed thereon to engage the bottom face of the rod 90 5. In this case the rod 5 would simply have a hole therein to receive the shank of the key.

From the above it will be seen that the spring tends to hold the switch points 95 against the rails of the main track so that if any parts should break the spring would close the switch and prevent derailment of the train. The reinforcements make the point as strong as any other part of the rail 100 and the reinforcements are firmly locked to the points so that there is no danger of them becoming separated from the points.

It is thought from the foregoing description that the advantages and novel features 105 of my invention will be readily apparent.

I desire it to be understood that I may make changes in the construction and in the combination and arrangement of the several parts, provided that such changes fall within 5 the scope of the appended claims.

What I claim is:—

1. In combination with a railroad switch, a reinforcing strip provided with a vertical opening longitudinally enlarged at the top, 10 a bridle rod provided with a longitudinal slot, a key having a head at each end adapted to be passed thru said opening and slot when the bridle rod and reinforcing strip are in parallel position and adapted to lock 15 said parts upon swinging the reinforcing strip to its position against a side and flange of the rail at right angles to the bridle rod, reinforcing strips mounted on said bridle rod having notched ends adapted to 20 engage the key shanks and flanges of the rails, a block mounted between the rails, a spring plunger mounted in said block, a cross piece mounted on said plunger, and rods connected with said cross piece bearing

under pressure of the spring plunger against 25 one of the rail reinforcing strips.

2. In combination with a railroad switch, a reinforcing strip mounted against a side and flange on each point thereof and provided with a vertical opening longitudinally 30 enlarged at the top, a bridle rod mounted between the switch rails and having an opening registering with that in the reinforcing strip, a key mounted thru said openings having a head to fit in the enlarged portion thereof, reinforcing strips mounted on the bridle rods and provided with notched ends to engage the shanks of the keys and said flanges, a block mounted between the switch points, a spring plunger 35 mounted in said block, a cross-piece mounted on said plunger and arms carried by said cross-piece adapted to bear against the reinforcing strip on the switch point under tension of the spring plunger. 40

In testimony whereof I affix my signature.

DAVIS A. PICKENS
